United States Patent Office

Des. 202,889

Patented Nov. 16, 1965

202,889

CABINET FOR WATER DISTILLATION APPARATUS

George H. Leamy, Horseheads, N.Y., assignor to Corning
Glass Works, Corning, N.Y., a corporation of New
York

Filed Feb. 18, 1965, Ser. No. 83,858

Term of patent 14 years

(Cl. D16—2)

Fig. 3

Fig. 2

Fig. 1

FIGURE 1 is an isometric view of a cabinet embodying
the design.

FIGURE 2 is a front view thereof.

FIGURE 3 is a side view thereof.

The back of the cabinet is substantially flat.

I claim:

The ornamental design for a cabinet for water distillation apparatus, as shown and described.
